United States Patent Office.

JAMES R. HALL, OF GEORGETOWN, ILLINOIS.

Letters Patent No. 71,745, dated December 3, 1867.

IMPROVED SASH-STOP.

The Schedule referred to in these Letters Patent and making part of the same.

TO ALL WHOM IT MAY CONCERN:

Be it known that I, JAMES R. HALL, of Georgetown, in the county of Vermillion, and State of Illinois, have invented an Improved Sash-Supporter and Fastener; and I do hereby declare that the following is a full, clear, and exact description thereof, which will enable others skilled in the art to make and use the same, reference being had to the accompanying drawings, forming part of this specification.

The present invention consists in a simple and novel attachment to sash or window-frames, for the support and fastening of the sash therein at any desired point in its play or movement. In the accompanying plate of drawings my improved sash-supporter or fastener is illustrated—

Figure 1 being an edge view of the same, and

Figure 2 a section taken on the plane of the line x x , fig. 1.

Similar letters of reference indicate corresponding parts.

A, in the drawings, represents the frame or holder carrying the parts constituting my improved sash-supporter or fastener. This frame consists of a face-plate, B, having applied to it two parallel projecting plates, C, in and between which is arranged a lever-catch, D, that, at one end, is retained by a bent spring, E, which projects out from the face-plate, and extends along its length, and is secured and fixed at its end F thereto. This catch, by its hook end G, is projected through an opening, H, in the face-plate B, when operated upon by the bearing of the roller I, eccentrically hung within and between the two plates C, in proper position to act against such catch; this roller being provided with a milled handle, J, for convenience in operating it.

From the description above, of my improved sash-supporter and fastener, it is plainly apparent that the spring E acts to support the sash, and the lever-catch, if properly thrown out, to not only support, but also to fasten the sash.

I claim as new, and desire to secure by Letters Patent—

The combination of the spring E and lever-catch G and eccentric roller I, substantially as and for the purpose described.

JAMES R. HALL.
